UNITED STATES PATENT OFFICE.

HENRY COWLES AND JAMES K. NORRIS, OF UTICA, NEW YORK, ASSIGNEES, BY MESNE ASSIGNMENTS, TO NATIONAL RADIATOR CORPORATION, OF DOVER, DELAWARE, A CORPORATION OF DELAWARE.

HEATING APPARATUS.

Application filed January 11, 1923. Serial No. 612,003.

Our invention relates to boilers or hot-water heating apparatus of the type in which auxiliary air is introduced into the combustion space for insuring complete combustion and thereby increasing efficiency and preventing smoke, and it attains these objects by causing the air before its delivery at the place where it is needed, to be properly heated during its passage thereto by extending the air conducting pipe or passage in and preferably through or across a fire gas flue through which products of combustion are passing and whereby the air is heated to the requisite extent and thence extending it through or in close relation to a water-containing space from which the air is directly admitted to its point of mixture with the fire gases to perfect the combustion of the latter. By this means, it is practical to admit air of adequate temperature, i. e. above the critical point or lower limit of temperature range where the most efficient combustion is secured; without danger of burning out the air pipe.

Our invention, in its preferred form, is embodied in a sectional furnace made up of a series of front, rear and intermediate cast, hollow, water-containing units or sections assembled to form a firebox, rear flue space and overhead return flues, all in communication, and provided with pipes for admitting auxiliary air, as above mentioned, which pipes deliver the air into the fire-gas flow, so as to perfect or stimulate the combustion reaction therein and are themselves subject to the temperature of the fire gases at points farther along in the path thereof and more remote from the region of maximum combustion.

Three forms which the apparatus may advantageously take are illustrated in the drawings in which Fig. 1 is a side elevation partly in section;

Fig. 2 a section on the line II—II of Fig. 1 looking toward the rear of the furnace as indicated by the arrows, part of the front wall of the adjacent section being broken away to show the interior construction;

Fig. 3 is a section on the line III—III Fig. 2 looking in the direction of the arrows;

Fig. 4 is a front view of a section illustrating a modification;

Fig. 5 is a section on the line V—V Fig. 4;

Fig. 6 is a section on the line VI—VI Fig. 4 looking in the direction of the arrows;

Fig. 7 is a fragmentary detail view of a

further modified form of my invention, which is similar to that of Fig. 1, but differs therefrom in the inclusion of a removable relatively enlarged flue-contained air-heating box; and

Fig. 8 is a perspective view of said air-heating box.

The sectional furnace herein illustrated corresponds in general to usual furnace construction of this type being made up of a series of cast, hollow, water-containing units or sections 1 bolted together and suitably supported as by the base members 2 at each side of the furnace; a rear plate 3, an intermediate plate 4 and a front plate 5 with usual door and damper arrangements completing the structure at the base and providing in advance of the plate 4 the usual ash pit. These sections are provided with flue openings, which in the assembled position are aligned to form the firebox 6, below which is located the grate 7, and above which are the overhead return side flues 8 and the central rearward overhead flue 9, together with communicating flue space 10 as indicated at the left of Fig. 1, the flow of the combustion products as indicated by the arrows in Fig. 1 being that usual in furnaces of this type. Some of the sections toward the front of the furnace provide the firebox and all of the intermediate sections form combustion and flue space communicating with the fire-box space. The external contour of all sections is the same but their structure is not identical. The front section is provided with the usual firebox openings or feed and clean-out doors 11. The rear section forms the rear wall of the furnace, as will be understood. An intermediate section 12 is formed so as to produce a throat passage through which the fire gases pass from the fire-box to the flue space. This section illustrated in Figs. 1 to 3 and, which in its main features shows the preferred form of the invention, is provided with aligned vertical cored passages 13 and 14 on each side of the furnace, into which the auxiliary air pipes 15 provided with dampers 15' are inserted, the construction being the same at each side. The air pipes so placed intersect the side flues 8 and are thus subjected for a part of their length to a high degree of heat, the temperature of these flues being greater than in the center flue, but less than in the fire-box or in its restricted throat outlet. The

lower ends of these pipes are surrounded by water space. The air is drawn from atmosphere, through these pipes, by the pull of the chimney draft, or otherwise, and into an air box or air chamber 16 which extends across the furnace and defines the bottom of water-curtain wall of section 12 and the top of the throat through which the fire gases pass. This air box is preferably water-surrounded on all sides and has a downward exit, either in the form of a continuous slot or of a series of downwardly delivering openings 17. The air is directed by this exit athwart the current of burning gases.

15 While the arrangement thus described is preferred, we may dispense with the air chamber and deliver the auxiliary air directly from the pipes 15 to the combustion space adjacent any section or sections, as in the construction illustrated in Figs. 4 to 6, wherein the section shown is one of those in advance of the throat section. Such a section may be employed with the throat section of Figs. 1 to 3 or with other throat sections. It is cast 25 with grooves 18, 19, preferably aligned vertically, 18 being above and 19 below the central flue space. The auxiliary air pipe 15 may be laid in these grooves during assembly. It is thus subjected to a cooling action as well as 30 to the heating effect of the flue gases. These pipes may be withdrawn from the furnace after assembly.

The form shown in Figs. 7 and 8 is a modification of that illustrated in Figs. 1 to 3, 35 and as to the features peculiar to Figs. 7 and 8, an improvement thereon. This construction differs from that of Figs. 1 to 3 in that the air pipe 15 does not extend through the flue, and enters it only far enough to communicate with a removable air-heating box 20 which is placed in the side flue and forms part of the passage for auxiliary air. It is enlarged relatively to the pipe 15 thereby providing an increased area of heating surface 40 and constituting in effect an enlarged extension of the pipe having an outlet at its bottom which is of a smaller section than the body of the box 20, and is shown as formed by a downwardly extending nipple 21 which fits 45 a corresponding depression in the bottom flue wall, said nipple being in alignment with the passage 14 to the cross air box 16. Should the air-heating box 20 burn out, it can be readily removed and replaced through the corresponding flue door in the front unit 1^a. The duct for delivering air to the air box or to the combustion space may include a plurality of 50 passages and be constituted in whole or in part by a separately made pipe. This arrangement of removable air-heaters may obviously also be employed in the center flue.

In each of the forms above described, it will be apparent that the greater part of the air for combustion of the fuel enters 55 through the grate, and that all the remainder,

herein termed auxiliary air, is admitted at the point of greatest velocity of the gas travel and directly into such gas. By this arrangement, the pull of the chimney will maintain an adequate inflow through the auxiliary air 70 pipes, sufficient to produce a thorough mixing and stimulated combustion. By the passage of such air through the fire-gases in the flues, at points relatively remote from the throat or region of maximum combustion, it becomes 75 heated highly enough so that it is not cooled, by its subsequent contact with water-cooled walls, to a temperature so low as to be incapable of the desired instantaneous combustive reaction. At the same time no part of 80 the air passage, which is near the very intense heat at the throat and in the fire-box, is left unprotected by water so as to be likely to burn out. It has been found that air passages entirely surrounded by water do 85 not heat the air to the desired point for the best combustion, but by the arrangement described, the air is adequately heated although delivered to the fire-gases from a water-cooled box or from immediate proximity to water- 90 cooled walls.

We claim as our invention:—

1. A sectional furnace comprising a longitudinal series of transverse hollow water-containing sections bolted together, having a grate and forming by aligned openings in adjacent sections a firebox and a longitudinal overhead flue, and an air duct leading from the atmosphere through water space to and through said flue, and through water space beyond the flue to the combustion space, being water protected at and adjacent its point of delivery to the fire gases, whereby the duct is protected against destructively high temperature and the air delivered by it heated to a point at which it does not chill the fire gases. 100

2. A sectional furnace comprising a series of hollow transverse water-containing sections forming a longitudinally extending firebox with water-cooled walls, an overhead flue space through which products of combustion therefrom pass, and a separately formed pipe passing imperforate through said flue space, partially water-cooled but protected from direct contact with water and functioning in the delivery of air to the combustion space at a point beyond the flue. 110

3. A sectional furnace comprising a series of hollow water-containing sections forming a firebox and flue, and a depending wall at the rear of said firebox and whose lower edge defines the throat through which the products of combustion pass, the throat section or sections having a transverse water-cooled air box provided with air distributing openings adjacent the region of maximum combustion and a duct for delivering air to said air box part of which duct is located in the flue and is thus highly heated and parts of which in advance of the flue and beyond the flue to the air box 125 130

are water-cooled and thereby protected against destructively high temperature and the air delivered by them heated to a point at which it does not chill the fire gases.

5 4. In a sectional furnace, a transverse hollow water-containing section forming overhead water-cooled flue openings, a water-cooled air box extending across the section below said flue openings and a fire box opening immediately below the air box, said section being provided with alined cored passages opening to a flue in opposite walls thereof, one of said passages opening to the atmosphere and the other to said air box, said passages being 10 adapted to receive a separately formed air pipe in heat exchanging relation with the walls of one of them, and said air pipe being in communication with the air box.

5 5. In a sectional furnace, a transverse hollow water-containing throat section having a flue opening in the upper part thereof and having below the same a depending wall ending in a transverse water-protected air delivery box defining the upper side of the throat 25 through which fire gases are intended to pass, said unit having water-cooled passages abutting on said flue opening adapted to receive in heat exchanging contact a separately formed air pipe which extends imperforate 20 in said flue opening from one of said passages to the other and communicates respectively with the atmosphere and with said air box, whereby said pipe and passages being water-cooled to their delivery ends are protected

against a destructively high temperature and the air delivered by them heated to a point at which it does not chill the fire gases. 35

6. In a sectional furnace, a transverse hollow water-containing section having a fire box opening and above the same a flue opening 40 separated from the fire box opening by a water-cooled portion of the section, said section having a portion adjacent the flue opening shaped to receive, and cool without direct water contact, a separately formed pipe extending imperforate across said flue opening and communicating with the fire box space. 45

7. In a sectional furnace, a transverse hollow water-containing throat section having three transversely alined flue openings in the 50 upper part thereof and having below the same a depending wall ending in a transverse water protected air delivery box defining the upperside of the throat through which fire gases are intended to pass, said unit having a pair 55 of water cooled passages abutting on each side flue opening, each such pair being adapted to receive, in heat exchanging contact with one of its members, a separately formed air pipe which extends in the flue opening from one passage to the other and communicates respectively with the atmosphere and with said air box. 60

In testimony whereof, we have signed this specification.

HENRY COWLES.
JAMES K. NORRIS.
